No. 12,629 Dec 27, 1881

UNITED STATES PATENT OFFICE.

H. CLAY BASCOM AND CYRUS A. HODGES, OF TROY, AND TOBIAS S. HEISTER, OF LANSINGBURG, ASSIGNEES TO N. S. VEDDER PATTERN WORKS, BASCOM, GALBRAITH & CO., OF TROY, NEW YORK.

DESIGN FOR A STOVE.

SPECIFICATION forming part of Design No. 12,629, dated December 27, 1881.

Application filed November 25, 1881. Term of patent 7 years.

To all whom it may concern:

Be it known that we, H. CLAY BASCOM and CYRUS A. HODGES, each a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for 10 Base-Burner Stoves, of which the following is a specification, reference being had to the accompanying cut, print, or engraving of a stove which embodies said new design.

The design for the crest A is composed of the 15 upper concavo-conical part, b, having a greater height than base-diameter, downwardly-tapering lower part, c, and intermediate fluted portion, d, in combination with the part e, extending along and conformed to opposite sides of 20 the part b, and having at the top the large central point, e', and smaller lateral points e'', and at the bottom the angular ornaments e''' and intermediate scalloped inner edges and outer edges of convexly and concavely curved form, 25 with intervening angles, all shaped and arranged substantially as shown in the accompanying print.

The design for the cover B consists of the concavely-curved upper part, f, the fillet-form 30 lower part, f', and the intermediate concavely-conical part, g, having thereon the particular series of pending cord ornaments h and scroll ornaments h', all shaped and arranged together as shown in the accompanying engraving.

The design for the panel ornament C consists of a swelled surface having parallel or 35 nearly parallel sides at right angles, or nearly so, to a downwardly-curved lower edge, and double concave upwardly-pointing top edge, 40 and the band i, extending diagonally from corner to corner, with a semi-rosette, j, and leaf j' in the diagonally-opposite obtuse angles, and the scroll-vine k, bent in a nearly circular form under and partly over the band j, and having 45 pinnate leaves k', all shaped and arranged together substantially as shown in the aforesaid cut.

The design for the outer portion of the panel D consists of the ornamental top bar, l, side 50 scrolls, l', and looped cord m, with tassels m'

pending from said bar and scrolls, in combination with the side ornaments, n, and pending cord ornaments n' with drop ornaments n'', all shaped and arranged together substantially as shown in the aforesaid print.

The design for the upper section consists of the panel ornaments C, each shaped and composed of the ornamental parts i j j' k k', as above specified, in combination with the panels D, each having the parts l l', m m', and n n' n'', all shaped and arranged so as to appear substantially as shown in the aforesaid engraving.

The design for the mica-light door E consists of the one middle mica-light aperture, o, extending in upwardly-tapering form at the upper part, from the lower bar, p, to the upper bar, p', in combination with and between the lateral lower quadrilateral mica-light apertures q q and the upper four-side mica-light openings q' q', said parts o and q q' q' being separated and surrounded by the sash-frame p p' r, and all shaped and arranged together so as to present substantially the appearance shown in the aforesaid cut.

The design for the open-work section F consists of the horizontal ring-like series of perforated or skeleton kidney-form ornaments s, in combination with the series of standards s', rising from the incurved upper sides of the ornaments s, and united at the tops in a series of 80 arches, with the series of ornaments t pending from the arches, and all shaped and arranged together substantially as shown in the aforesaid print.

The design for the lower mica-light doors, G, 85 consists of the raised, oblong, curved, rectangular panels u, each formed with two mica-light apertures, v, each having parallel upright sides and obtuse-angled bottom and top edges and greater length horizontally than vertically, and 90 surrounded and separated by the compound moldings v', all shaped and arranged together substantially as shown in the aforesaid cut.

The design for the rear side flue-plate, H, consists of the upper ornament, w, lower sprig ornaments, w', and intermediate pending cord-and-tassel ornaments w'', all shaped and arranged together substantially as shown in the aforesaid print.

The design for the ash-pit section I consists 100

of the front and lateral inclined terraced side parts, x , having rounded corners, with the ornaments x' thereon, the series of serrate-terrace ornaments x^2 , bottom ornamental border, 5 x^3 , and front draft-apertures, x^4 , having contracted tops, and all shaped and arranged substantially as shown in the aforesaid engraving.

The design for the legs consists of the upper swelling panel, y , having the upper pending 10 cord-and-drop ornament, y' , and bottom ornament y^2 , in combination with the lower swelling-panel, z , having the pending cord-and-drop ornament z' , and all shaped and arranged substantially as shown in the aforesaid print.

15 What we claim as our joint invention is—

1. The design for the crest A, consisting of the parts $b c d$, in combination with the parts $e e' e^2 e^3$, all shaped and arranged together, as set forth.

20 2. The design for the cover B, composed of the parts $f f' g h h'$, all shaped and arranged together as set forth.

25 3. The design for the panel ornament C, consisting of the form shown, in combination with the ornamental parts $i j j' k k'$, all shaped and arranged together as set forth.

30 4. The design for the outer portion of the panel D, consisting of the ornamental parts $l l' m m' n n' n^2$, all shaped and arranged together as set forth.

35 5. The design for the upper section, consisting of the panel ornaments C, shaped and ornamented as specified, in combination with the panels D, ornamented as described, and all arranged together as set forth.

6. The design for the mica-light doors E, each composed of the long upwardly-tapering middle mica light, o , and the four lateral mica lights $q q' q' q'$, all surrounded and separated by the frame $p p' r$, and shaped and arranged together as set forth. 40

7. The design for the open-work section F, the same being of the general convex form shown, and composed of the ornamental parts $s s' t$, all shaped and arranged together as set 45 forth.

8. The design for the lower mica-light doors, G, composed of the parts $u v v'$, all shaped and arranged together as described and shown.

9. The design for the rear side flue-plate, H, 50 consisting of the parts $w w' w^2$, all shaped and arranged together as set forth.

10. The design for the ash-pit section I, composed of the parts $x x' x^2 x^3 x^4$, all shaped and arranged together as set forth. 55

11. The design for the legs, composed of the parts $y y' y^2 z z'$, all shaped and arranged together as set forth.

In testimony whereof we hereunto set our hands, in the presence of two subscribing witnesses, this 22d day of November, 1881. 60

H. CLAY BASCOM.
CYRUS A. HODGES.
TOBIAS S. HEISTER.
